US00D933494S

(12) **United States Design Patent** (10) **Patent No.:** **US D933,494 S**
Tempfli et al. (45) **Date of Patent:** **** Oct. 19, 2021**

(54) **PACKAGING BOTTLE FOR LIQUIDS**

(71) Applicants: **Karl Tempfli**, Gottmadingen (DE);
Volker Heinzle, Krauchenwies (DE);
Magdalena Orasche, Freyung (DE)

(72) Inventors: **Karl Tempfli**, Gottmadingen (DE);
Volker Heinzle, Krauchenwies (DE);
Magdalena Orasche, Freyung (DE)

(73) Assignee: **Aptar Radolfzell GmbH**, Radolfzell
(DE)

(**) Term: **15 Years**

(21) Appl. No.: **29/675,091**

(22) Filed: **Dec. 28, 2018**

(30) **Foreign Application Priority Data**

Jul. 10, 2018 (EM) 005499258

(51) **LOC (13) Cl.** **09-01**

Primary Examiner — Lauren R Calve*(74) Attorney, Agent, or Firm* — Flynn Thiel, P.C.(57) **CLAIM**

The ornamental design for a packaging bottle for liquids, as shown and described.

DESCRIPTION

FIG. 1 is a perspective view of a packaging bottle for liquids showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

1 Claim, 6 Drawing Sheets
